AUTOMATIC ELECTRIC SELECTIVE SILVER
COIN CHANGER

Leonard L. Pruy, Los Angeles, Calif.

Application November 4, 1946, Serial No. 707,735

1 Claim. (Cl. 194—10)

1

This invention relates to coin changers, and more particularly to an automatic electric selective silver coin changer.

The general object of the invention is to provide a novel coin changer, which upon depositing silver coins of different denominations therein, will automatically deliver the correct change of said coins in coins of smaller denominations.

Another object is to provide a coin changer of the character stated, which cannot be operated by slugs or coins other than silver coins, and will automatically throw out slugs or such other coins.

Other objects and advantages will appear hereinafter as this specification progresses.

The invention is illustrated in the annexed drawings which form a part of this specification and in which:

Fig. 1 is a front elevation of my coin changer.

Fig. 2 is a transverse vertical section of my coin changer taken on line 2—2 of Fig. 1.

Fig. 3 is a horizontal section of my coin changer taken on line 3—3 of Fig. 2.

Fig. 4 is a fragmentary transverse vertical section taken on line 4—4 of Fig. 3 showing the lower part of the magazine for containing half dollars or fifty-cent coins.

Fig. 5 is a fragmentary transverse vertical section taken on line 5—5 of Fig. 3, showing the lower part of the magazine for containing quarters or twenty-five cent coins.

Fig. 6 is a fragmentary transverse vertical section taken on line 6—6 of Fig. 3 showing the lower part of the magazine for containing dimes or ten cent coins.

Fig. 7 is a fragmentary transverse vertical section taken on line 7—7 of Fig. 3 showing the lower part of the magazine for containing nickels or five cent coins.

Fig. 8 is a fragmentary transverse vertical section taken on line 8—8 of Fig. 3 showing the lower part of the magazine for containing pennies.

Fig. 9 is a plan view of the coin-selecting mechanism.

Fig. 10 is a vertical longitudinal section of the coin-selecting mechanism taken on line 10—10 of Fig. 9.

Fig. 11 is an edge view of Fig. 10, looking at the left edge of Fig. 10.

Fig. 12 is a general wiring diagram of the electrical circuits of my coin changer.

Fig. 13 is a wiring diagram of the motor actuating unit.

Fig. 14 is a wiring diagram of one of the unit coin-selecting circuits.

2

Fig. 15 is a plan of one of the partitions of the magazines.

Fig. 16 is a view of the key for turning the magazine partitions shown in Fig. 15.

Fig. 17 is a longitudinal section of one of the coin-releasing solenoids.

Referring more particularly to the drawings, in which the same parts are designated by the same reference numerals in all of the figures, my invention includes generally a casing 1, which may be of cylindrical form; a plurality of coin magazines 2, 3, 4, 5 and 6 enclosed within said casing; coin-delivery mechanisms 7, 8, 9, 10 and 11 for said magazines, respectively, within said casing; a plurality of coin-selecting mechanisms 12, 13, 14, 15 and 16; coin-actuated switches 17, 18, 19, 20 and 21 controlling circuits hereinafter described, for operating said coin-delivery mechanisms; coin chutes 22, 23, 24, 25 and 26, and 27; coin-delivery chutes 28, 29, 30 and 31; slug chutes 32, 33, 34, 35, and 36; coin-collecting chutes 37, 38, 39, 40 and 41; coin-collecting receptacles 42, 43, 44, 45 and 46 into which lead said coin-collecting chutes, respectively; an electrical motor actuating unit 47; an electric motor 48 driven by said unit 47 and controlled by said coin-actuated mechanisms for operating said coin-delivery mechanisms in the manner hereinafter described; a coin-delivery funnel 49 into the upper and larger end of which lead said coin-delivery chutes 28, 29, 30 and 31 and the slug chute 34; and a coin-delivery receptacle 50 into which leads the lower smaller end of said coin-delivery funnel 49, said coin-delivery receptacle being located outside of the front part of the vertical cylindrical wall of the casing 1 near the bottom of said casing. The slug chutes 32 and 33 lead into the coin-delivery chutes 28 and 29, respectively. The slug chutes 35 and 36 lead into the coin-delivery chute 31. The coin chutes 22 and 23 lead into the coin-delivery chutes 28 and 29, respectively. The coin chute 24 leads into the coin-delivery chute 30. The coin chute 25 leads into the coin chute 26, and the coin chute 26 leads into the coin-delivery chute 31. In the upper part of the vertical cylindrical wall of the casing 1 are provided coin-receiving slots 51, 52, 53, 54 and 55 for receiving silver dollars, half dollars, quarters, dimes and nickels, respectively, for actuating the machine to deliver change for said coins, respectively, in the manner hereinafter described. From said coin-receiving slots 51, 52, 53, 54 and 55 lead coin chutes 56, 57, 58, 59 and 60, respectively, to the coin-selecting mechanisms 12, 13, 14, 15 and 16, respectively.

35

40

45

50

55

60

Each of said coin-selecting mechanisms includes a coin-selecting receiver 61, Fig. 14, a silver-coin collecting solenoid 62, a slug-ejecting solenoid 63, a relay switch 64, a silver-coin rheostat 65, a silver-coin circuit battery 66, a slug-ejecting rheostat 67, a slug circuit battery 68, and a coin-actuated switch 69. The silver-coin collecting solenoid 62 is actuated by a coin-collecting circuit 70. The slug-ejecting solenoid 63 is actuated by a slug-ejecting circuit 71. The relay switch 64 is actuated by a relay circuit 72. The coin-selecting receiver 61 includes two bridge bars 73 and 74 extending at right angles to each other and secured, respectively, at one end to the adjacent ends of the cores 75 and 76 of the silver coin-selecting solenoid 62 and the slug-ejecting solenoid 63, respectively, with the bridge bar 74 spaced above the bridge bar 73 sufficiently to receive a silver coin or a slug therebetween. The bridge bar 73 is formed with up-turned ends 77 and 78, between which ends a silver coin may be received while resting upon the bridge bar, and the intermediate portion 79 of said bridge bar is formed of insulating material which electrically insulates from each other the ends 77 and 78 of the bridge bar. The end 78 of the bridge bar 73, while secured to the adjacent end of the core 75 of the solenoid 62, is electrically insulated from said core by a strip of insulation 80 interposed between the end 78 of the bridge bar 73 and said end of said solenoid core 75. The bridge bar 74 is formed with down-turned ends 81 and 82, between which ends a slug may be received while resting upon the bridge bar 73, and the intermediate portion 83 of the bridge bar 74 is formed of insulating material which electrically insulates from each other said ends 81 and 82 of said bridge bar 74. The end 82 of the bridge bar 74, while secured to the adjacent end of the core 76 of the slug-ejecting solenoid 63 is electrically insulated from said core by a strip of insulation 84 interposed between said end 82 of the bridge bar 74 and said end of said solenoid core 76. Each coin-actuated switch 69 includes a terminal contact 85 and a spring contact 86, which spring contact normally rests out of engagement with said terminal contact within the lower end of a coin chute 56, 57, 58, 59 or 60 of a coin-selecting mechanism 12, 13, 14, 15 or 16, respectively.

The coin-actuated switch 17 includes a plurality of terminal contacts 87, 88, 89, 90 and 91, and a triangular swingable contact 92 pivoted at its upper corner at 93 to one side of the coin-collecting chute 37, so that one of its sides 94 normally extends from said side of said chute downwardly to the other side of said chute as clearly shown in Fig. 13.

The coin-actuated switch 18 includes a plurality of terminal contacts 95, 96, 97 and 98, and a triangular swingable contact 99, similar to contact 92 of switch 17, pivoted at its upper corner at 100 to one side of the coin-collecting chute 38, with one of its sides extending downwardly in said chute to the other side thereof.

The coin-actuated switch 19 includes a plurality of terminal contacts 101, 102 and 103, and a triangular swingable contact 104, similar to contact 92 of switch 17, pivoted at its upper corner at 105 to one side of the coin-collecting chute 39, with one of its sides extending downwardly in said chute to the other side thereof.

The coin-actuated switch 20 includes two terminal contacts 106 and 107, and a triangular swingable contact 108, similar to contact 92 of switch 17, pivoted at its upper corner at 109 to 75

45

one side of the coin-collecting chute 40, with one of its sides extending downwardly in said chute to the other side thereof.

The coin-actuated switch 21 includes two terminal contacts 110 and 111, and a triangular swingable contact 112, similar to contact 92 of switch 17, pivoted at its upper corner at 113 to one side of the coin-collecting chute 41, with one of its sides extending downwardly in said chute to the other side thereof.

The coin magazine 2 is mounted in the casing 1 on brackets 114 secured to the inner side of the casing wall and said magazine is formed with a plurality, preferably five, coin compartments 115 extending longitudinally and vertically therethrough of suitable diameter to receive half dollars. The magazine 2 includes a stationary disc 116 secured to the lower end of the magazine body 117 in slightly spaced relation by means of a screw bolt 118 and nut 119, which bolt is threaded in the lower end of said magazine body at 120 and said nut is threaded on the lower end of said bolt against the lower side of said disc 116. The bolt 118 is formed with a short cylindrical portion 121 on which is turnably fitted a pulley 122 in the space between the lower end of the magazine body 117 and the disc 116 with the periphery of said pulley extending beyond the periphery of said disc. The portion 121 of the bolt 118 is slightly larger than the lower shank portion of the bolt, providing a shoulder 123 at the lower end of said portion 121 against which portion shoulder the disc 116 is held by the nut 119 in spaced relation to the lower end of the magazine body 117. The disc 116 is provided with an opening 124 of the same diameter as the magazine compartments 115, and the pulley 122 is provided with an opening 125 of the same diameter as said compartment, said opening 125 being arranged to register with the lower end of said compartments and with the opening 124 in the disc 116 in the manner and for the purpose hereinafter described. Extending under the opening 124 in the disc 116 is a slide 126 connected to the core of a solenoid 127, which slide prevents any coin from dropping through said opening 124 in said disc until the slide is withdrawn from under said opening by said solenoid (see Fig. 4).

The coin magazine 3 is mounted in the casing 1 by brackets 3' and is of the same construction as that of the magazine 2, except that its coin compartments 128 are of a size to contain quarters. The openings 129 and 130 in the disc 131 and pulley 132, respectively, are of the same diameter as the coin compartments 128, and the slide 133 extending under the disc opening 129 is connected to the core of a solenoid 134 (see Fig. 5).

The coin magazine 4 is mounted in the casing 1 by brackets 135 and is of the same construction as that of the magazine 2, except that its coin compartments 136 are of a size to contain dimes, the openings 137 and 138 in the disc 139 and pulley 140, respectively, are of the same diameter as the coin compartments 136, and the thickness of the disc 139 is equal to the thickness of two dimes, so that the disc opening 137 will hold two dimes, and the slide 141 extending under the disc opening 137 is connected to the spring return core of a solenoid 142.

The coin magazine 5 is mounted in the casing 1 on a bracket 143 and is of the same construction as that of the magazine 2 except that its coin compartments 144 are of a size to contain nickels, while a disc 145 is substituted for the

disc 116 and a pulley 146 is substituted for the pulley 122. The disc 145 is provided with two openings 147 and 148 of the same diameter as that of the compartments 144, and the thickness 149 of the disc 145, through which the opening 147 extends, is of the thickness of one nickel, so that the opening 147 will receive only one nickel, while the thickness 150 of said disc, through which the opening 148 extends, corresponds to the thickness of two nickels, so that said opening 148 will hold two nickels. The pulley 146 is provided with two openings 151 and 152 of the same diameter as the coin compartments 144 and are adapted to register with the lower ends of said compartments in the manner hereinafter described. Extending under the opening 147 in the disc 145 is a slide 153 connected to the core of a solenoid 154, while a slide 155 extends under the opening 148 in said disc 145, which slide 155 is connected to the spring-return core of a solenoid 156. Said slides 153 and 155 prevent nickels from dropping through the disc openings 147 and 148, respectively.

The coin magazine 6 is mounted in the casing 1 by brackets 157 and is of the same construction as that of the magazine 4 except that its coin compartments 158 are of a size to contain pennies, the openings 159 and 160 in its disc 161 and pulley 162, respectively, are of the same diameter as the coin compartments 158 and the thickness of said disc 161 is equal to the thickness of five pennies, so that said disc opening 159 will hold five superimposed pennies, and the slide 163 extending under the disc opening 159 is connected to the core of a spring-return solenoid 164. There is only one opening 159 in the disc 161, and a plurality of circumferentially-spaced openings 160 in the pulley 162, equal in thickness to that of a penny.

In slots 165 and 166 in the body 117 of each of the magazines 2 to 6, inclusive, are turnably mounted disc coin partitions 167 and 168, respectively, on pins 167' and 168', respectively, which slots are so spaced that said partitions therein divide each magazine into three superimposed sections 169, 170 and 171, with the section 169 located at the lower end of the magazine, the section 170 located above the section 169, and the section 171 located above the section 170. The disc partitions 167 and 168 are provided with openings 172 corresponding, respectively, in size, number and location to the coin compartments in the magazines 2 to 6, inclusive. Each disc partition 167 and 168 is provided with a notch 173 in its periphery to receive a key 174 to turn said partitions into position in which the openings 172 therein register or do not register with the coin compartments in the magazines 2 to 6, respectively, in the manner hereinafter more fully described. Normally when the openings 172 in the disc partitions 167 and 168 do not register with the magazine coin compartments, the coins in said compartments in the intermediate sections 170 of the magazines are supported upon the disc partitions 167, which takes the weight of said coins off the coins in the coin compartments in the lower magazine sections 169, while the coins in the coin compartments in the upper sections 171 of the magazines are supported upon the disc partitions 168, which takes the weight of the coins in said upper sections off the coins in the compartments in the intermediate sections 170 of the magazines, so that the weight only of the coins in the compartments in the lower sections 169 of the magazines rests upon the pulleys 122.

132, 140, 146 and 162, respectively, at the lower end of the magazines, which facilitates the functioning of said pulleys in delivering the coins from said magazines. The casing 1 is provided with a series of horizontal slots 175 opposite the magazine disc partitions 167, respectively, and a series of horizontal slots 176 opposite the magazine disc partitions 168. One end of each of the slots 175 is enlarged at 177, which enlargement is positioned directly opposite the notch 173 in the disc partition 167 opposite the slot 175, when said partition is in position with its openings 172 in registration with the coin compartments in the magazine in which the partition is located, so that the key 174, when inserted through said enlargement 177, will engage the notch 173 in the disc partition, for turning the partition to shift its openings 172 out of registration with the magazine coin compartments. One end of each of the slots 176 is enlarged at 178, which enlargement is positioned directly opposite the notch 173 in a disc partition 168 opposite the slot 176, when said partition is in position with its openings 172 in registration with the coin compartments in the magazine in which the partition is located, so that the key 174, when inserted through said enlargement 178, will engage the notch 173 in the disc partition for turning the partition to shift its opening 172 out of registration with the magazine coin compartments.

On the shaft 179 of the motor 48 are secured a plurality of pulleys 180, 181, 182, 183, 184 and 185. A belt 186 extends over the pulley 180 and the pulley 122 at the lower end of the magazine 2, whereby the pulley 122 is rotated by the motor 48 in the manner hereinafter described. A belt 187 extends over the pulley 181 and the pulley 132 at the lower end of the magazine 3. A belt 188 extends over the pulley 182 and the pulley 140 at the lower end of the magazine 4. A belt 189 extends over the pulley 183 and the pulley 145 at the lower end of the magazine 5. A belt 190 extends over the pulley 184 and the pulley 162 at the lower end of the magazine 6. A belt 191 extends over the pulley 185 and a pulley 192 of a rotary switch 193 of a motor control circuit 194, whereby said rotary motor switch is rotated by the motor 48 for actuating said motor control circuit, in the manner and for the purpose hereinafter more fully described.

The electrical motor actuating unit 47 includes the motor control circuit 194, a motor power circuit 195, a relay actuating circuit 196 for said motor power circuit, and a motor switch opening circuit 197 for breaking said motor power circuit at the end of each revolution of said motor. The motor power circuit 195 includes a generator 198, an armature switch 199 comprising an armature contact 200 and a terminal contact 201, a lead 202 extending from said terminal contact 201 to one pole of the generator 198, a lead 203 extending from the other pole of said generator to one brush 204 of the motor 48, and a lead 205 extending from the other brush 206 of said motor to the armature contact 200. The relay actuating circuit 196 as shown in Fig. 12 partly includes a pair of electro-magnets 207 and 208 at one side of the armature contact 200 of switch 199, from one end of the coils 209 and 210, respectively, of which solenoids extend leads 211 and 212, the other ends of which solenoid coils being connected by a lead 213. The rotary switch 193 includes the pulley 192 of insulating material, a plate contact 214 secured on one side of said pulley, and a pair of brush contacts 215 and 216, for wiping

said pulley and plate contact. The circuit 197 includes a generator 217, an electro magnet 218, and the rotary motor switch 193. From one pole of the generator 217 extends a lead 219 to the brush contact 215 of the rotary motor switch 193. From the other pole of said generator 217 extends a lead 220 to one end of the coil 221 of the solenoid 218. From the other end of said solenoid coil extends a lead 222 to the brush contact 216 of the rotary motor switch 193. The solenoid 218 is on the side of the armature 200 of switch 199 opposite the side on which the relay coils 207 and 208 are located.

The coin-actuated switch 17 actuates four coin changer circuits 223, 224, 225 and 226 and the relay motor actuating circuit 196.

The coin changer circuit 223 includes the switch 17, a lead 228, extending from the contact 91 of said switch to one end of the coil of solenoid 156, a lead 229 extending from the other end of said solenoid coil to a lead 230, a generator 231 to one pole of which is connected said lead 230, and a lead 232 extending from the other pole of said generator to the swingable contact 92 of the coin-actuated switch 17, there being a control switch 233 interposed in said lead 232.

The coin-changer circuit 224 includes the switch 17, a lead 234 extending from the contact 98 of said switch to one end of the coil of the solenoid 142, a lead 235 extending from said solenoid coil to the lead 230, the generator 231 to one pole of which said lead 230 is connected, the lead 232 extending from the other pole of said generator switch 233 and swingable contact 92 of the coin-actuated switch 17.

The coin-changer circuit 225 includes the switch 17, a lead 236 extending from the contact 89 of said switch to one end of the coil of the solenoid 134, a lead 237 extending from the other end of said solenoid coil, the lead 230 to which said lead 237 is connected, generator 231, lead 232, switch 233 and swingable contact 92 of said switch 17.

The coin-changer circuit 226 includes the switch 17, a lead 238 extending from the contact 88 of said switch to one end of the coil of the solenoid 121, a lead 239 extending from the other end of said solenoid coil, the lead 230 to which said lead 239 is connected, generator 231, lead 232, switch 233 and swingable contact 92 of said switch 17.

The relay motor-actuating circuit 196, to be actuated by the coin-actuated switch 17, includes completely said switch, a lead 240 extending from the contact 87 of said switch to a lead 241, the lead 211 extending from said lead 241 to the motor actuating unit 47, relay solenoid coil 209, lead 213, relay solenoid coil 210 in said unit, lead 212 extending from said unit, lead 242, generator 47', lead 243, and lead 244 to the swingable contact 92 of said switch 17.

The coin-actuated switch 18 actuates three coin changer circuits 245, 246 and 247 and the relay motor-actuating circuit 196.

The coin-changer circuit 245 includes the switch 18, a lead 248 extending from the contact 98 of said switch to the lead 228, lead 229, the coil of solenoid 156, lead 229, lead 230, lead 249, a generator 250, lead 251, and the swingable contact 99 of the switch 18.

The coin-changer circuit 246 includes the switch 18, a lead 252 extending from the contact 97 of said switch to the lead 234, lead 234, the coil of solenoid 142, lead 235, lead 230, lead 249,

generator 250, lead 251 and the swingable contact 99 of the switch 18.

The coin-changer circuit 247 includes the switch 18, a lead 253 extending from the contact 96 of said switch to the lead 236, the coil of solenoid 134, lead 237, lead 230, lead 249, generator 250, lead 251, and the swingable contact 99 of the switch 18.

The relay motor-actuating circuit 196 to be actuated by the coin-actuated switch 18, includes completely said switch, a lead 254 extending from the terminal contact 95 of said switch to the lead 241 to the motor actuating unit 47, lead 211 extending from said lead 241, coil 209 of relay solenoid 207, lead 213, relay solenoid coil 210 in said unit, lead 212 extending from said unit, lead 242, generator 47', lead 243, lead 244 and lead 255 to the swingable contact 99 of said switch 18.

The coin-actuated switch 19 actuates two coin changer circuits 256 and 257 and the relay motor-actuating circuit 196.

The coin-changer circuit 256 includes the switch 19, a lead 258 extending from the contact 103 of said switch to the lead 228, lead 229, the coil of solenoid 156, lead 229, lead 230, a lead 259, a generator 260, a lead 261 and the swingable contact 104 of the switch 19.

The coin-changer circuit 257 includes the switch 19, a lead 262 extending from the contact 102 of said switch to the lead 234, lead 234, the coil of solenoid 142, lead 235, lead 230, lead 259, generator 260, lead 261 and swingable contact 104 of said switch 19.

The relay motor-actuating circuit 196 to be actuated by the switch 19 includes completely said switch, a lead 263 extending from the terminal contact 101 of said switch to the lead 241, lead 241, lead 211 to the motor actuating unit 47, coil 209 of relay solenoid 207, lead 213, coil 210 of relay solenoid 208 of said unit, lead 212 extending from said unit, lead 242, generator 47', lead 243, lead 244 and a lead 264 to the swingable contact 104 of said switch 19.

The coin-actuated switch 20 actuates one coin-changer circuit 265 and the relay motor-actuating circuit 196.

The coin-changer circuit 265 includes the switch 20, a lead 266 extending from the terminal contact 107 of said switch to the coil of solenoid 155, said solenoid coil, a lead 267 extending from said solenoid coil, lead 230, a lead 268, a generator 269, a lead 270 and the swingable contact 108 of said switch 20.

The relay motor-actuating circuit 196 to be actuated by the switch 20 includes said switch, a lead 271 extending from the terminal contact 106 of said switch to the lead 241, lead 241, lead 211 to the motor actuating unit 47, coil 209 of relay solenoid 207, lead 213, coil 210 of relay solenoid 208 of said unit, lead 212 extending from said unit 47, lead 242, generator 47', lead 243, lead 244, and a lead 272 and the swingable contact 108 of the switch 20.

The coin-actuated switch 21 actuates one coin-changer circuit 273 and the relay motor-actuating circuit 196.

The coin-changer circuit 273 includes the switch 21, the lead 274 extending from the terminal contact 111 of said switch to the coil of solenoid 164, said solenoid coil, the lead 230, a lead 275, a generator 276, a lead 277 and the swingable contact 112 of said switch 21.

The relay motor-actuating circuit 196 to be actuated by the switch 21 includes the lead 241 extending from the terminal contact 110 of said

switch, lead 211 extending to the motor actuating unit 47, coil 209, of the relay solenoid 207, lead 213, coil 210 of relay solenoid 208 of said unit, lead 212 extending from said unit, lead 242, generator 47, lead 243, lead 244 and lead 278 and the swingable contact 112 of the switch 21.

The coin-collecting circuit 10 (Fig. 14) of each coin-selecting mechanism 12, 13, 14, 15 and 16 includes the generator 66, from one pole of which extends a lead 280 to the contact end 77 of the bridge bar 73 of the coin-selecting receiver 61 of one of said coin-selecting mechanisms. From the contact end 78 of the bridge bar 73 extends a lead 281 to one end of the coil 282 of the silver coin-collecting solenoid 62, from the other end of which coil extends a lead 283 to the terminal of the armature 284 of the relay switch 64, which armature normally engages a terminal contact 285, but is adapted to engage a terminal contact 286 when swung upwardly by the electromagnets 287 and 288 of said relay switch 64. From the terminal contact 286 extends a lead 289 to one end of the resistance coil 290 of the rheostat 65. From the contact arm 291 of said rheostat extends a lead 292 to the other pole of the generator 66. From the outer end of the core 75 of the silver coin-selecting solenoid 62 of each coin-selecting mechanism extends a rod 293 through a bearing 294 on the inside of the casing 1, and a spring 295 surrounds said rod 293, bearing at one end against said bearing 294 and at its other end against the outer end of the core 75 of said solenoid 62, which spring 295 normally holds the bridge bar 73 of the coin-selecting receiver 61 in its initial position to receive a silver coin from the chute 56, 57, 58, 59 or 60 of any coin-selecting mechanism 12, 13, 14, 15 or 16, respectively.

The slug-ejecting circuit 71 of each coin-selecting mechanism 12, 13, 14, 15 and 16 includes the generator 68, from one pole of which extends a lead 296 to the armature 284 of the relay switch 64, and from the contact 285 of which switch extends a lead 297 to the end contact 81 of the bridge bar 74 of the coin receiver 61 of one of said coin-selecting mechanisms. From the end contact 82 (Fig. 9) of said bridge bar 74 extends a lead 298 to one end of the coil 299 of the slug-ejecting solenoid 63, from the other end of which coil extends a lead 300 to the contact arm 301 of the rheostat 67, and from one end of the resistance coil 302 of said rheostat extends a lead 303 to the other pole of the generator 68. From the outer end of the core 76 of the slug-ejecting solenoid 63 extends a rod 304 through a bearing 305 on the inner side of the casing 1, and a coil spring 306 surrounds said rod 304, bearing at one end against the outer end of the core 76 of said solenoid 63 and at its other end against said bearing 305, which spring 306 normally holds the bridge bar 74 of the coin-selecting receiver 61 in its initial position to receive a slug from the chute 56, 57, 58, 59 or 60 of any coin-selecting mechanism 12, 13, 14, 15 or 16, respectively.

The relay circuit 72 of each coin-selecting mechanism 12, 13, 14, 15 or 16 includes a generator 307, from one pole of which extends a lead 308 to one end of the coil of an electromagnet 287 of a relay switch 64, from the other end of which coil extends a lead 309 to one end of the coil of the other electromagnet 288 of said relay switch 64, and from the other end of said coil of said magnet 288 extends a lead 310

to the contact 85 of the coin-actuated switch 69 of the relay circuit 72 of each coin-selecting mechanism 12 to 16, respectively. From the contact 86 of the coin-actuated switch 69 of the relay circuit 72 of each of said coin-selecting mechanisms, respectively, extends a lead 311 to the other pole of the generator 307 of said relay circuit 72.

In Fig. 17 is shown the spring-return coin-releasing solenoid 127 for releasing coins from the magazine 2 for making change, which solenoid comprises a core sleeve 312, a core 313 slidably fitted in said sleeve, and a coil 314 wound on said core sleeve, to the ends of which coil are connected the leads 238 and 239, and to the outer end of which core 313 is connected the slide 126 for supporting or releasing coins in the magazine 2. On the ends, respectively, of the core sleeve 312 are formed a head 315 and a flange 316, which head closes one end of the core sleeve 312, while an opening 317 is formed centrally of said flange 316 in communication with the other end of said core sleeve 312, through which opening extends the core 313 into said sleeve. A coil spring 318 is located in the core sleeve 312, bearing at one end against the sleeve head 315 and at its other end against the inner end of the core 313 for normally projecting said core outwardly. The coil 314 is wound on the core sleeve 312 between the sleeve head 315 and the sleeve flange 316. The solenoids 134, 142, 154, 156 and 164 are of the construction as solenoid 127.

The operation of my invention is as follows:

To make change of a silver dollar the dollar is introduced into the coin-receiving slot 51 in the upper part of the casing 1 of the machine and into the upper end of the coin chute 56 of the coin-selecting mechanism 12, whereupon the dollar slides down said chute over the spring contact 86 of the coin-actuated switch 69 and into the coin-selecting receiver 61 of said coin-selecting mechanism 12. As the dollar slides down said chute 56 and passes over said spring contact 86 it depresses said contact into engagement with the contact 85 of said switch 69, and closes said switch and the relay circuit 72, and the dollar then passes into the coin-selecting receiver 61 under the bridge bar 74 and upon the bridge bar 73 between the contacts 77 and 78, whereupon the electric current of the relay circuit 72 passes from the generator 307 through lead 308, the coil of relay magnet 287, lead 309, the coil of relay magnet 288, lead 310, closed switch 69 and lead 311 to the other pole of said generator 307, and the armature 284 of the relay switch 64 is swung up by the energized magnets 287 and 288 into engagement with the contact 286 of said relay switch, which closes the coin-selecting circuit 10. Electric current then passes through said circuit 10 from one pole of the generator 66 through the lead 280, the contact 77 of the coin-selecting receiver 61, the silver dollar in said receiver, the contact 78 of said receiver, lead 281, the coil 282 of the silver-coin-collecting solenoid 62, lead 283, armature 284 and contact 286 of the relay switch 64, lead 289, resistance 290 and arm 291 of rheostat 65 and lead 292 to the other pole of the generator 66, whereupon the solenoid 62 draws the bridge bar 73 and its contacts 77 and 78, together with the silver dollar on said bridge bar, over the upper end of the coin-selecting chute 37 and the silver dollar, passing from under the bridge bar 74 and resting eccentrically upon the bridge bar 73 in

unstable equilibrium, drops off said bridge bar into the upper end of the coin-collecting chute 37 and down said chute into the coin-collecting receptacle 42. As the dollar drops down said chute 37 it engages the inner edge 94 of the swingable contact 92 of the coin-actuated switch 17 and swings said contact outwardly into engagement with the terminal contacts 87, 88, 89, 90 and 91 of said switch 17, closing the coin-changer circuits 223, 224, 225 and 226 and the motor power relay actuating circuit 196, and energizing the coin-releasing solenoids 154, 142, 134 and 127, which solenoids withdraw the coin-supporting slides 153, 141, 133 and 116 from under the coin magazines 5, 4, 3 and 2, respectively, while the magnets 207 and 208 of said relay actuating circuit 196 close the switch 199 and the motor-power circuit 195 controlled by said switch. Thereupon the motor 48, through its shaft 179 and pulleys 180, 181, 182, 183 and 184, and the belts 186, 187, 188, 189 and 190 rotates the magazine pulleys 122, 132, 140 and 146, until the opening 125 in pulley 122, in which opening rests a half dollar on disc 116, registers with the opening 124 in said disc; the opening 130 in pulley 132 in which opening rests a quarter on the disc 131, registers with the openings 129 in said disc; two successive openings 138 in pulley 140, in which opening rest two dimes respectively on the disc 139, adapted to register successively with the opening 137 in said disc which opening 137 is equal in height to the thickness of two superimposed dimes and to the thickness of the disc 139; and the opening 151 in pulley 146, in which opening rests one nickel on the disc 145. Thereupon said half dollar drops through said opening 124 in magazine disc 116, through coin chute 22, coin delivery chute 28 and coin-delivery funnel 49 into the coin-delivery receptacle 50; said quarter drops through said opening 129 in 40 magazine disc 131, coin chute 23, coin-delivery chute 29, and coin-delivery funnel 49 into the coin-delivery receptacle 50; said two dimes drop through the opening 137 in magazine disc 139, coin-delivery chute 24 and coin-delivery funnel 49 into the coin-delivery receptacle 50; and said nickel drops through said opening 153 in magazine disc 145, coin chute 26, coin-delivery chute 31 and coin-delivery funnel 49 into the coin-delivery receptacle 50, thus making and delivering complete change of the silver dollar deposited in the machine as above described, which change is then removed from said coin-delivery receptacle 50 by the depositor of said dollar in the machine as above described.

When the motor 48 is driven to rotate the delivery pulleys 122, 132, 140 and 146 of the magazines 2, 3, 4 and 5 to deliver change of a dollar, as aforesaid, the pulley 192 of the rotary switch 193 is rotated by the motor 48, through its shaft 179, pulley 185 and belt 191, so that the switch arm contacts 215 and 216 wipe the insulated pulley 192 and break the motor switch-opening circuit 197, until the contact plate 214 is rotated under said switch arm contacts and said circuit is closed by the rotary switch 193, whereupon the electromagnet 218 is energized and swings down the armature 200 out of engagement with the contact 201, opening the switch 199 and breaking the motor power circuit 195, which 70 causes the motor 48 to stop and arrest further rotation of the magazine pulleys 122, 132, 140, 146 and 162, with the coin-receiving openings 125, 130, 138, 152 and 160 in said magazine pulleys, respectively, directly under the lower 75

ends of the coin compartments 115, 128, 136, 144 and 158, respectively, of the coin magazines 2, 3, 4, 5 and 6, whereupon a half dollar drops from the coin compartment 115 into the pulley opening 125 onto the disc 116 of the magazine 2; a quarter drops from the coin compartment 128 into the pulley opening 130 onto the disc 131 of magazine 3; two dimes drop from the coin compartment 136 into openings 138 onto the disc 139 of magazine 4; and a nickel drops from a coin compartment 144 into the opening 151 onto the disc 145, which completes the cycle of operations of the machine for making and delivering change of a silver dollar, and the machine is set for making change of other silver coins.

If a slug, the size of a silver dollar, should be inserted in the slot 51, said slug will slide down the chute 56 over the switch contact 86 into the coin-selecting receiver 61 upon the bridge bar 73 and under the bridge bar 74, with the edges of the slug engaging the end contacts 77 and 78 of the bridge bar 73 and the edges of the slug also engaging the end contacts 81 and 82 of the bridge bar 74. The slug in sliding down the chute 56 over the switch contact 86 depresses said contact and closes the switch 69 and the relay circuit 72, energizing the relay magnets 287 and 288, which swing the relay armature 284 up into contact with the contact 286, closing the relay switch 64 of the silver-coin circuit 70, but the slug, when it slides into the coin selecting receiver 61 and its edges engage the contacts 77 and 78, the slug fails to complete the closing of the silver-coin circuit 70 because of the resistance of the slug and the adjustment of the rheostat 65 to the resistance of a silver dollar, and the solenoid 62 fails to draw its core 75 and the bridge bar 73 together with the slug into position to drop the coin into the coin-collecting chute 37. The slug after passing the switch contact 86 and sliding into the coin-selecting receiver 61 enables the spring contact 86 to spring back into its upper position and open the switch 69 and break the relay circuit 72, which deenergizes the relay magnets 287 and 288 and allows the relay armature 284 to drop away from the contact 286 upon the contact 285 of the relay switch 64, closing the slug-ejecting circuit 71, so that electric current passes from one pole of the battery 68 through lead 303, rheostat 67 adjusted to the low resistance of said slug, lead 300, coil 299 of slug-ejecting solenoid 63, lead 298, end contact 82 of bridge bar 74 of coin-selecting receiver 61, the slug resting upon said bridge bar 55 of said coin-selecting receiver, end contact 81 of said bridge bar, lead 297, contact 285 and armature 284 of relay switch 64 and lead 296 to the other pole of the battery 68. Thereupon the core 76 of slug-ejecting solenoid 63 and the bridge bar 74, together with the slug on said bridge bar, are drawn by the coil 299 of said solenoid toward said coil until said bridge bar and said slug are brought directly over the upper end of the slug chute 32, and the slug resting at one side of its center upon said bridge bar in unstable equilibrium drops off said bridge bar into the upper end of said slug chute and drops down said chute and the coin-delivery chute 28 into the coin-delivery receptacle 50, thus ejecting the slug and preventing it from surreptitiously operating the machine.

To make change of a half-dollar a half-dollar is inserted in the slot 52 of the coin-selecting mechanism 13, which half-dollar slides down the chute 57 of said mechanism into its coin-

selecting receiver 61, and while sliding down said chute said half-dollar closes the switch 69 and the relay circuit 72 of said mechanism, which causes the armature 284 of the relay switch 64 of said circuit to swing upwardly into engagement with the contact 286 and close the coin-collecting circuit 70 of said mechanism, whereupon the coin-collecting solenoid 62 of said circuit, draws the bridge bar 73 of said coin-selecting receiver, together with the half-dollar on said bridge bar over the upper end of the coin-collecting chute 38, into and down which chute said coin drops into the coin-collecting receptacle 43. In dropping down said chute said half-dollar engages and swings the triangular contact 99 into engagement with the contacts 95, 96, 97 and 98, closing the coin-actuated switch 18, the coin-changer circuits 245, 246, and 247 and the motor power circuit relay-actuating circuit 196 and energizing the coin-releasing spring-return solenoids 154, 142 and 134, and the magnets 207 and 208 of said relay actuating circuit 196, which solenoids withdraw the coin-supporting slides 153, 141 and 133 from under the coin magazines 5, 4 and 3, respectively, while the magnets 207 and 208 of said relay actuating circuit 196 close the switch 199 and the motor power circuit 195 controlled by said switch. Thereupon the motor 48, through its shaft 179 and pulleys 181, 182, 183 and 184, and the belts 187, 188, 189 and 190 rotates the magazine pulleys 132, 140 and 146, until the opening 130 in pulley 132, in which opening rests a quarter on the disc 131, registers with the opening 129 in said disc; the opening 138 in pulley 140, in which opening rests two dimes on the disc 139, registers with the opening 137 in said disc; and the opening 151 in the pulley 146, in which opening rests a nickel on the disc 145, registers with the opening 147 in said disc. Thereupon said quarter drops through said opening 129 in magazine disc 131, coin chute 23, coin-delivery chute 29, and coin-delivery funnel 49 into the coin-delivery receptacle 50; said two dimes drop through the opening 137 in the magazine disc 139, coin-delivery chute 24 and coin-delivery funnel 49 into the coin-delivery receptacle 50; and said nickel drops through said opening 147 in magazine disc 145, coin chute 26, coin-delivery chute 31 and coin-delivery funnel 49 into the coin-delivery receptacle 50, thus making and delivering complete change of the silver half-dollar deposited in the machine as above described.

When the coins, which make the change of the half-dollar, as aforesaid, drop from the magazines which contain them, the motor power circuit 195 is broken and the motor 48 stops as above described in the operation of the machine in making change of a dollar, and the machine is set for making change of other silver coins.

If a slug, the size of a half dollar, should be inserted in the slot 52, said slug will slide down the chute 58 into the coin-selecting receiver 61 of the coin-selecting mechanism 13, which mechanism is actuated by the slug to prevent the slug from dropping down the coin-collecting chute 38 and closing the switch 18 of the circuits controlling the coin-delivery mechanisms for making change of a half dollar, but said coin-selecting mechanism 13 is actuated to drop said slug from said coin-selecting receiver 61 into and through the coin chute 33, coin-delivery chute 29 and coin-delivery funnel 49 into the coin-delivery receptacle 50, thus ejecting the slug and preventing it from making change of a half-dollar in the manner in which the coin-

selecting mechanism 12 ejects a slug deposited therein to make change of a dollar, as above described.

To make change of a quarter, a quarter is inserted in the slot 53 of the coin-selecting mechanism 14, which quarter slides down the chute 58 of said mechanism into its coin-selecting receiver 61, and while sliding down said chute said quarter closes the switch 69 and the relay circuit 72 of said mechanism, which causes the armature 284 of the relay switch 64 of said circuit to swing upwardly into engagement with the contact 286 and close the coin-collecting circuit 70 of said mechanism. Thereupon the coin-collecting solenoid 62 of said circuit draws the bridge bar 73 of said coin-selecting receiver 61, together with said quarter on said bridge bar over the upper end of the coin-collecting chute 39, into and down which chute said quarter drops into the coin receptacle 44, and in dropping down said chute said quarter engages and swings the triangular contact 104 into engagement with the contacts 101, 102 and 103, closing the coin-actuated switch 19, the coin-changer circuits 256 and 257, and the motor power circuit relay-actuating circuit 196 and energizing the coin-releasing spring-return solenoids 154 and 142, and the magnets 207 and 208 of said relay-actuating circuit 196, which solenoids withdraw the coin-supporting slides 153 and 141 from under the coin magazines 5 and 4, respectively, while the magnets 207 and 208 of said relay actuating circuit 196 close the switch 199 and the motor power circuit 195 controlled by said switch. Thereupon the motor 48, through its shaft 179 and pulleys 182 and 183, and the belts 188 and 189, rotates the magazine pulleys 140 and 146 until the opening 138 in pulley 140, in which opening rests two dimes on the disc 139, registers with the opening 137 in said disc, and the opening 151 in the pulley 146, in which opening rests a nickel on the disc 145, registers with the opening 147 in said disc, whereupon said two dimes drop through the opening 137 in the magazine disc 139 and through the coin-delivery chute 24 and coin-delivery funnel 49 into the coin-delivery receptacle 50, while said nickel drops through the opening 147 in the magazine disc 145 and through the coin chute 26, coin-delivery chute 31 and coin-delivery funnel 49 into the coin-delivery receptacle 50, thus making and delivering complete change of said silver quarter deposited in the machine as above described.

When the coins which make the change of the quarter, as aforesaid, drop from the magazines which contain them, the motor power circuit 195 is broken and the motor 48 stops, as above described, in the operation of the machine in making change of a dollar, and the machine is set for making change of other silver coins.

If a slug, the size of a quarter, should be inserted in the slot 53, said slug will slide down the chute 58 into the coin-selecting mechanism 14, which mechanism is actuated by said slug to prevent the slug from dropping down the coin-collecting chute 39 and closing the switch 19 of the circuits controlling the coin-delivery mechanisms for making change of a quarter, but said coin-selecting mechanism 14 is actuated to drop said slug from said coin-selecting receiver 61 into and through the slug chute 34 and coin-delivery funnel 49 into the coin-delivery receptacle 50, thus ejecting the slug and preventing it from making change of a quarter, in the manner in which the coin-selecting mechanism 12 ejects a slug de-

posited therein to make change of a dollar, as above described.

To make change of a dime, a dime is deposited in the slot 54 of the coin-selecting mechanism 15, which dime slides down the chute 59 of said mechanism unto its coin-selecting receiver 61, and while sliding down said chute said dime closes the switch 69 and the relay circuit 72 of said mechanism, which causes the armature 284 of the relay switch 64 of said circuit to swing upwardly into engagement with the contact 286 and close the coin-collecting circuit 70 of said mechanism. Thereupon the coin-collecting solenoid 62 of said circuit draws the bridge bar 73 of said coin-selecting receiver 61, together with said dime on said bridge bar over the upper end of the coin-collecting chute 40, into and down which chute said dime drops into the coin receptacle 45, and in dropping down said chute said dime engages and swings the triangular contact 108 into engagement with the contacts 106 and 107, closing the coin-actuated switch 20, the coin-changer circuit 265, and the motor power circuit relay-actuating circuit 196 and energizing the coin-releasing spring-return solenoid 156 and the magnets 207 and 208 of said relay-actuating circuit 196, which solenoid withdraws the coin-supporting slide 155 from under the magazine 5, while the magnets 207 and 208 of said relay actuating circuit 196 close the switch 199 and the motor power circuits 195 controlled by said switch. Thereupon the motor 48, through its shaft 179 and pulley 183, and the belt 189, rotates the magazine pulley 146, one complete revolution, whereby the opening 152 in said pulley is rotated away from the opening 148 in said disc and said pulley 146 covers the upper end of said opening, in which opening 148 rest two nickels and during such rotation of said pulley 146 the solenoid 156 withdraws its slide 155 from under the lower end of said opening 148, whereupon said two nickels drop through said opening 148 and down through the coin chute 26, coin-delivery chute 31 and coin-delivery funnel 49 into the coin-delivery receptacle 50, thus making change of said dime deposited in the machine as above described.

When the two nickels, which make the change of the dime, as aforesaid, drop from the magazine 5, the motor power circuit 195 is broken and the motor 48 stops, as above described in the operation of the machine in making change of a dollar, and the machine is set for making change of other silver coins.

If a slug, the size of a dime, should be deposited in the slot 54 said slug will slide down the chute 59 into the coin-selecting mechanism 15, which mechanism is actuated by said slug to prevent said slug from dropping down the coin-collecting chute 40 and closing the switch 20 and the circuit 265 controlling the coin-delivery mechanism for making change of a dime, but said coin-selecting mechanism 15 is actuated to drop said slug from said coin-selecting receiver 61 into and through the slug chute 35, coin-delivery chute 31, and coin-delivery funnel 49 into the coin-delivery receptacle 50, thus ejecting the slug and preventing it from making change of a dime in the manner in which the coin-selecting mechanism 12 ejects a slug deposited therein to make change of a dollar as above described.

To make change of a nickel, a nickel is deposited in the slot 55 of the coin-selecting mechanism 16, which nickel slides down the chute 60 of said mechanism into its coin-selecting receiver 61, and while sliding down said chute said nickel

closes the switch 69 and the relay circuit 72 of said coin-selecting mechanism, which causes the armature 284 of the relay switch 64 of said circuit to swing upwardly into engagement with the contact 286 and close the coin-collecting circuit 70 of said mechanism, whereupon the coin-collecting solenoid 62 of said circuit draws the bridge bar 73 of said coin-selecting receiver 61, together with said nickel on said bridge bar over the upper end of the coin-collecting chute 41, into and down which chute said nickel drops into the coin-collecting receptacle 46, and in dropping down said chute said nickel engages and swings the triangular contact 112 into engagement with the contacts 110 and 111, closing the coin-actuated switch 21, the coin-changer circuit 273, and the motor power circuit relay-actuating circuit 196 and energizing the coin-releasing spring-return solenoid 164 and the magnets 207 and 208 of said relay-actuating circuit 196, which solenoid 164 withdraws the coin-supporting slide 163 from under the opening 159 in the disc 161 under the pulley 162 and magazine 6, whereupon the five pennies in said opening 159 drop out of said opening down through the coin chute 27, coin-delivery chute 31, and coin-delivery funnel 49 into the coin-delivery receptacle 50, making change of a nickel, and as the nickel drops past the triangular switch member 112, said member swings back out of engagement with the contacts 110 and 111, opening the switch 21 and breaking the coin-delivery circuit 273 and the motor relay-actuating circuit 196, and deenergizing the coin-collecting solenoid 164, so that its spring projects its core and slide 163 back under the lower end of the coin opening 159 in the disc 161, while the magnets 207 and 208 of said motor relay-actuating circuit 196 close the switch 199 and the motor power circuit 195, controlled by said switch, whereupon the motor 48, through its shaft 179 and pulley 184, and the belt 190, rotates the magazine pulley 162, until five successive openings 160 in said pulley 162 register successively with the lower end of a coin compartment 158 in magazine 6 and successively with the upper end of the coin opening 159 in the disc 161, so that five pennies drop from said coin compartment through said pulley openings 160 into said disc opening 159 upon the slide 163 of the coin-collecting solenoid 164, and the motor 48, through its shaft 179 and pulley 185, and the belt 191, rotates the pulley 192 of the rotary switch 193 with the switch arm contacts 215 and 216 wiping the insulated pulley 192 and maintaining open the motor switch-opening circuit 197, until the contact plate 214 is rotated under said switch arm contacts 215 and 216, and said motor switch-opening circuit 197 is closed by the rotary switch 193, energizing the magnet 218, which swings down the armature 200 out of engagement with the contact 201 and opens the switch 199, breaking the motor power circuit 195 and bringing the motor 48 to rest, which arrests further rotation of the magazine pulley 162 and the pulley 192 of the rotary switch 193, with said switch closing the motor switch-opening circuit 197 and thereby breaking the motor control circuit 194, and thus sets the operating mechanism of the penny magazine 6 for repeating its operation for delivering five pennies from said magazine as above described.

If a slug, the size of a nickel, is deposited in the slot 55 said slug will slide down the chute 59 into the coin-selecting mechanism 16, which mechanism is actuated by said slug to prevent

said slug from dropping down the coin-collecting chute 41 and closing the switch 21 and the circuit 273 for controlling the coin-delivery mechanism for making change of a nickel, but said coin-selecting mechanism 16 is actuated to drop said slug from said coin-selecting receiver 61 into and through the slug chute 36, coin-delivery chute 31 and coin-delivery funnel 49 into the coin-delivery receptacle 56, thus ejecting the nickel slug and preventing it from making change of a nickel in the manner in which the coin-selecting mechanism 12 ejects a slug deposited therein to make change of a dollar, as above described.

I claim:

In a coin changer, a magazine formed with a vertical coin compartment, a partition turnably mounted in said magazine between the lower and upper ends of the magazine, said partition being provided with an opening therein arranged to register with said coin compartment or not according to the position to which said partition is turned, a pulley turnably mounted below the lower end of said magazine and provided with an opening therein arranged to register with the lower end of said compartment when the pulley is in its initial position, a stationary disc below said pulley provided with an opening out of registration with said coin compartment, a slide normally resting under said opening in said stationary disc, said compartment being adapted to receive coins stacked in said compartment below said partition with the lowermost coin resting upon said stationary disc in the opening in said pulley, said compartment being adapted to receive coins stacked in said compartment above said partition with the lowermost of said coins resting upon said partition when in its position with its opening out of registration with said coin compartment, a drive pulley, a belt extending over said drive pulley and said pulley under said magazine, coin-receiving means actuated by a coin deposited therein to be changed, means, operated by said coin-receiving means when a coin is deposited therein, for rotating said drive pulley, whereby the pulley under said magazine is rotated through said belt to bring the opening in said pulley and the coin therein into register with the opening in said stationary disc, so that said coin will drop from said pulley opening into the opening in said stationary disc upon said slide,

and means operated by said coin-receiving means when said coin is deposited therein, for withdrawing said slide from under said opening in said stationary disc, to permit said coin in said opening to drop therefrom, and means for turning said partition to bring its opening into register with said coin compartment to permit coins in said coin compartment above said partition to drop through said partition opening into said coin compartment below said partition to replace coins ejected from said compartment below said partition the means for turning the partition in the coin magazine comprising a partition provided with a notch in its edge, a casing enclosing the coin magazine and provided with a slot therein with one end of said slot in registration with said notch in said partition, when said partition is turned so that its opening registers with the coin compartment, and a key adapted to be inserted through said slot into said notch for turning said partition to cause the partition opening to register or not with said coin compartment.

LEONARD L. PRUYN.
